UNITED STATES PATENT OFFICE.

WILLIAM H. AMES, OF WATSONVILLE, CALIFORNIA.

REFRIGERATOR-CASE.

SPECIFICATION forming part of Letters Patent No. 700,720, dated May 27, 1902.

Application filed May 6, 1901. Serial No. 59,037. (No model.)

To all whom it may concern:

Be it known that I, WILLIAM H. AMES, a citizen of the United States, residing at Watsonville, county of Santa Cruz, State of California, have invented an Improvement in Refrigerator-Cases; and I hereby declare the following to be a full, clear, and exact description of the same.

My invention relates to refrigerator-cases for the preserving and transportation for long distances of perishable goods and fruits, also to provide a package that shall be convenient and serviceable for the retail trade after same has reached its destination.

15 The invention consists in the parts and the constructions and combinations of parts, which I will hereinafter describe and claim.

Figure 1 is a vertical sectional view of my device, showing the door removed for a more perfect illustration, the arrangement of the ice-receptacle, slides on which the usual baskets of fruit or other goods may be placed, the movable slats in front covering the two lower sections of baskets and adapted to be continued the full height of fruit, the wood covering of the ice-pan, and the space at center and sides for the circulation of air. Fig. 2 is a plan view. Fig. 3 is a vertical sectional view on line *a a*, showing the arrangement of baskets and fruit in place, a slide partially withdrawn, the ice-receptacle and ice, the circulation of warm air over top, cold air out the bottom of pan, drain-tube for waste water, trap in door for discharge of same. Fig. 4 is a perspective vertical sectional drawing more fully illustrating the body, corners, slides, slats in front, and grooved strips in which they are sprung. Fig. 5 is a view of front, with the door closed, the locking device, the trap, the corner-pieces, and the ventilator. Fig. 6 is a perspective view of ice-pan and covering of wood. Fig. 7 is a view of tray or slide on which the baskets rest, showing the arrangement of slatted bottom, ledge, or raised portion to retain baskets in place, projecting ends to form space for circulation of air at front and back. Fig. 8 is a detail plan view of metal corner as cut and punched before bending. Fig. 9 is a perspective view of same after being bent. Fig. 10 is a detail view of

locking device. Fig. 11 is a detail of drainage-tube trap, with its extension of flexible tube.

In the accompanying drawings the same reference characters indicate the same parts of 55 the invention.

The box or case A may be made of any desirable shape or size. B denotes its door, hinged thereto. The sides and door of case are preferably made of thin material, two or 60 more pieces crossed and nailed or glued together and set into corner-pieces *b* for the purpose of making a stronger case.

C is an ice-receptacle surrounded on all sides and bottom with a thin wood covering 65 *c* for the purpose of preventing the moisture from condensing on outside of pan C and dripping off on fruit.

d is a drain-tube from pan C, connecting when door is closed with discharge-pipe and 70 trap E and flexible tube F for the discharge of waste water entirely away from the case.

e shows a low stationary front of ice-pan C; *f*, the movable front provided to swing on pivot *g* and attached to inside of ice-pan C. 75 The function of this movable front *f* is to swing up close under top of case A, as shown in Fig. 3, for the convenient filling of the ice-pan C with ice, after which it is drawn down, 80 its lower or bent edge just falling inside of the low stationary front *e*, making a closed pan to the height of the other sides, the purpose being both for the retaining of the ice and the controlling of the circulation of the air.

85 G is a narrow rim or ledge entirely surrounding the central opening in bottom of ice-pan.

I is a cap attached to suitable pieces to support same above rim G and projecting slightly 90 above same, with its top either curved or bent from the center to allow air to pass under and down through bottom, also to protect ice falling through the curved or bent shape to carry over to pan any condensed moisture that may 95 form on its under side.

In Fig. 4 the shape and manner of attaching guide-strips K to case A is clearly shown, with a portion of its side next to case cut away for the free circulation of air.

100

W shows vertical strips in center, to which are attached the center guide-slides k and arranged to leave a space between.

m shows locking-iron bolted to corner-strip 5 b with bolts at o o.

l shows latch bolted to door B by bolt o; R, plate under latch to prevent wear of wood when in use.

Locking-iron m is made with its upper off-
10 set made slightly longer than the lower one, so that when bolted to case it presents a wedge shape on its inside face with the wider part up, the action being that so soon as latch l is started under its upper end and is
15 forced down, as shown in Fig. 5, it forces the door in on its beveled edges, thereby making a very close joint between door and case and also making the case much more rigid than would otherwise be the result. To lock the
20 door, simply pass a padlock P through locking-iron m above the latch l, when latch cannot be removed.

Figs. 8 and 9 show the corners to be nailed to case A over the corners b, both for protection against wear and to more thoroughly stiffen the box.

S shows the movable tray, with its slatted bottom T, raised rim s for the retention of baskets.

30 X shows the thin strips in front of baskets, forming wall-sections to prevent the escape of cold air when the door is open; L, the grooved pieces at side into which slats X are sprung. To put slats X in place, insert one
35 end of same in the groove L, spring the center out on a curve till same is shortened enough to slip in groove on opposite side, when by releasing same it straightens back and fills the groove. To remove, grasp the
40 center and simply pull out the slat.

Heretofore the baskets have been removed from top of box only, causing much trouble to remove the ice-pan to reach the berries. With this case the seller simply springs out
45 the top slat X, when the top row of baskets is exposed and readily accessible by simply opening the door. After those are disposed of the action is repeated till the case is empty. The slides S and slats X are thrown in the case
50 and returned to shipper.

V represents handles to lift case by.

I do not confine myself to this exact description, but have shown what I believe to be the best manner of accomplishing the desired results.

55 I do not limit myself to the particular means here shown, whereby the ends of the slats X are simultaneously moved from the grooves; but my invention is broad enough to cover
60 any means whereby the ends of said slats may be simultaneously moved both inward or in opposite directions, whereby the slats can be

removed from the grooves without either sliding them upward or downward in said grooves or by removing one side of the groove.

Having thus described my invention, what I claim as new, and desire to secure by Letters Patent, is—

1. A case of the character described with top, bottom and three sides fixed together, the door hinged thereto, an ice-pan located near the top with a short side in front, three sides extending higher up, a center opening through bottom of ice-pan, a rim surrounding center opening, a cap placed above center opening, 75 a movable front attached to sides of ice-pan in such a way as to be raised up to open the front, a drain-tube attached to the bottom of ice-pan, a covering of wood or other suitable material, a trap and discharge-pipe connecting therewith, a flexible tube extending through the case, substantially as described.

2. A refrigerator-case having sides, top, bottom, and door, an ice-pan and drainage-tube, slides at the sides having portions of their 85 length removed for the free circulation of air, central upright pieces, slides attached to said central pieces spaced from each other to permit circulation of air and trays sliding on said slides, substantially as described.

90 3. A refrigerator-case having sides, top, bottom and door, an ice-pan and drainage-tube, slides supported at the sides and spaced therefrom to permit free circulation of air, central upright pieces, slides on said central pieces 95 spaced therefrom with the like object, and trays sliding on said slides, substantially as described.

4. A refrigerator-case comprising an ice-pan located near the top with a short side in front and three sides of greater height, a movable front attached to the sides of the ice-pan so that it can be raised to open the front, a central opening through the bottom of the ice-pan, a drain-tube therefrom, and a trap and 105 discharge-pipe connected therewith, substantially as described.

5. A refrigerator-case comprising an ice-pan, slides, trays on said slides, grooved upright side pieces near the door of the case, and 110 strips of suitable flexible material corresponding in height to the height between the slides, the ends of said strips being inserted in said grooves, and movable therefrom by flexing or springing the strips from said grooves whereby the strips may be removed from the grooves without sliding the same up or down, substantially as described.

In witness whereof I have hereunto set my hand this 23d day of March, 1901.

WILLIAM H. AMES.
